FUEL SAVING DEVICE FOR INTERNAL COMBUSTION ENGINES

Arthur W. Kushinsky, Chicago, Ill.

Application March 10, 1936, Serial No. 68,032

2 Claims. (Cl. 123—124)

Among the objects of my invention are to create an automatic, attachable device adapted to be added to any internal combustion engine for saving fuel consumption, which combines the feature of saving gas when the operator takes his foot off the accelerator with the added feature of saving gas during high speeds, and such other objects, advantages and capabilities as will later more fully appear and which are inherently possessed by my invention.

While I have shown in the accompanying drawing a preferred embodiment of my invention yet I wish it understood that the same is susceptible of modification and change without departing from the spirit of my invention.

Referring more particularly to the drawing: Fig. 1 is a diagrammatic figure showing my invention mounted in place on an automobile engine and the electrical circuit shown thereon; Fig. 2 is a longitudinal cross-section of my invention; and Fig. 3 is a plan section taken on the line 3—3 of Fig. 2.

As stated in my Patent Number 2,035,237 of March 24, 1936, in Fig. 1 I show the floor boards 10 and the cowl 11 through which passes the clutch pedal 12 of an ordinary automobile. Preferably underneath the floor boards of the car is located a battery 13 having a wire 14 grounded to the frame of the car at 15. At the opposite side of the battery 13 a wire 16 leads to contact springs 17 which are fixed to the floor boards 10 by suitable means such as bolts 18 and insulated therefrom. The contact springs 17 are closed when the clutch pedal 12 is in clutch engaged position. Leading from the contact springs 17 is another wire 19 leading to second contact springs 20, which springs are fixed by suitable fastening means 21 to a bracket which is attached to the carburetor bolt 22 and insulated therefrom. When the accelerator rod 23 is in released position the contacts of contact springs 20 are closed by the adjustable stop 24 on accelerator rod 23. Leading from contact springs 20 a wire 25 leads to one side of the solenoid winding 26 so that electrical current may pass through the winding of said solenoid 27 to the other side 28 of the solenoid to locking contact spring 29, said locking contact spring being insulated by suitable insulating material, and from locking contact spring 29 to wire 30 which leads to contact screw 31, which is suitably insulated from vacuum unit 33. When a high vacuum is created in the manifold 32 the vacuum unit 33 is operated making contact at 31 which completes the circuit, (vacuum unit 33 is grounded to the motor, and

the motor is grounded to the frame) energizing the solenoid 27 which operates the plunger 34 raising the same so that locking spring 29 makes contact on a washer or the like 34a of said plunger 34 to establish a secondary circuit locking the solenoid in the operated position.

This invention differs from my Patent No. 2,035,237 of March 24, 1936, in that a bolt 35 is fixed into the plunger 34, has a protruding head 36, and extends downwardly below the bottom of said plunger 34, and travels within the collar valve stem 56 of the valve 38. When the plunger 34 travels upwardly the bolt 36 likewise travels upwardly within the valve stem of the valve 38 as far as stop member 59 to expose opening 55. Within the hollowed out stem 56 of valve 38 lies movable piston 52. A resilient member such as a spiral spring 53 has its upper end contacting the piston 52 and its lower end held by shoulder 57 of the stem 56. The valve 38 at its head portion 58 has an opening 55 and from the stem portion 56 another opening 54. The opening 55 leads to the manifold chamber 40, and the opening 54 leads to the atmosphere.

As previously stated in my Patent No. 2,035,237 of March 24, 1936, in use let us assume that the driver is using a speed of some 30 miles per hour and desires to take his foot off the accelerator pedal and slow down. Ordinarily this operation would create a high vacuum in the manifold which would cause a sucking of gas into the manifold and hence into the motor which would result in great waste. In my structure instead of this gas going into the manifold, when the operator takes his foot off the accelerator, air instead of gas is admitted into the manifold. The contact springs 20 are closed so that the circuit is prepared for contact 31 due to vacuum in chamber 51 to complete the secondary circuit and the operation of vacuum unit 33 completes said circuit and actuates the solenoid so as to raise the plunger 34 and the valve 38 to permit air coming in through ports 41 into my chamber 40 connecting with the manifold. In use it is also apparent that as soon as the foot of the operator again moves to accelerate the car the contact springs 20 will be automatically opened and the circuit to the solenoid 27 will be broken restoring valve 38 to normal closed position, whereupon gas will be fed from the carburetor to the motor. On the other hand as an added safety feature, if the operator does not press the accelerator pedal, or change the clutch position from that shown in Fig. 1, air continues to be drawn into the motor, so that in time it will die. This is important

where the operator is suddenly incapacitated, and will result in saving of life and property.

It will be further noted that the vacuum unit 33 is preferably encased for protection in keeping contacts clean and workable. Said casing 42 comprises a plate 43 secured to coupling 44 by means of screws 45 and having at its outer end a ring 46 suitably secured thereto, and housing or cover member 47 which will slip over said ring 46. In the wall of said housing 47 is a slot 48 to slip over hollow nipple 49 and the coupling 44 is screw threaded for engagement, and the coupling 44 has a port 50 in communication with the chamber 40. Vacuum tube 51 of vacuum unit 33 is secured to the outer end of nipple 49 by means of solder or the like.

This invention differs from my Patent No. 2,035,237 of March 24, 1936, in that in non-operated position piston 52 is held up by springs 53 against screw head 35 which acts as a stop member exposing hole 54. When the motor is operated, piston 52 is drawn down by the vacuum, closes hole 54 and thus prevents the admission of air. Thus at constant load when the motor is running at high speed the vacuum in the manifold will decrease. This will allow spring 53 which has a given tension, to push piston 52 upward part way allowing some air to enter through port 54, and when the motor is running at its highest speed the vacuum will decrease more in proportion to allow spring 53 to push piston 52 all the way up, and completely expose hole 54 to obtain the maximum admission of air therein. Piston 52 will return again and close hole 54 when vacuum in the manifold is increased. Port 54 is smaller than port 55 so that spring 53 acting on piston 52 may be drawn down by suction in chamber 40.

Having thus described my invention I claim:

1. In combination with an internal combustion engine and an electrical source of supply, a fuel saving device adapted to be attached to the manifold of said internal combustion engine comprising an air intake structure having a plurality of air inlet ports and a chamber communicating with said manifold, said chamber having an opening, a valve with valve stem controlling said opening, means including a plunger adapted to move said valve to close said opening when the accelerator of the internal combustion engine is actuated, and to expose said opening when the accelerator is released, including a solenoid operatively connected with said plunger, an electric

circuit adapted to energize said solenoid, and a vacuum unit adapted upon the creation of a high vacuum caused by the release of the accelerator to contact said solenoid to instantly actuate said plunger to open the valve until pressure again applied to the accelerator breaks the circuit and returns the valve to closed position, said valve having a casing with an upper opening adjacent its stem portion leading to the atmosphere and a lower opening adjacent its head portion leading to the manifold, a piston movable within the upper part of said stem portion of the valve, a resilient member within the lower part of said stem portion of the valve and having its upper end contacting the piston and its lower end held by a shoulder of the head portion of the valve, said piston normally positioned by said resilient member when the engine is not running to expose the upper opening for admitting air but said piston adapted to be pulled downwardly by vacuum when the engine is running to close said upper opening, said resilient member having tension sufficient to push said piston upwardly as the vacuum is decreased by the increased speed of the running engine so as to expose said upper opening in proportion to the increased speed for admitting air into the valve casing and thence through the lower opening into the manifold.

2. In a fuel saving device adapted to be attached to the manifold of an internal combustion engine, a valve and valve stem having a casing with an upper opening adjacent its stem portion leading to the atmosphere and a lower opening adjacent its head portion leading to the manifold, a piston movable within the upper part of said stem portion of the valve, a resilient member within the lower part of said stem portion of the valve and having its upper end contacting the piston and its lower end held by a shoulder of the head portion of the valve, said piston normally positioned by said resilient member when the engine is not running to expose the upper opening for admitting air but said piston adapted to be pulled downwardly by vacuum when the engine is running to close said upper opening, said resilient member having tension sufficient to push said piston upwardly as the vacuum is decreased by the increased speed of the running engine so as to expose said upper opening in proportion to the increased speed for admitting air into the valve casing and thence through the lower opening into the manifold.

ARTHUR W. KUSHINSKY.
